UNITED STATES PATENT OFFICE.

JAMES S. COPELAND, OF HARTFORD, CONNECTICUT, ASSIGNOR TO THE
POPE MANUFACTURING COMPANY, OF SAME PLACE.

DESIGN FOR A CRANK-SHAFT BRACKET.

SPECIFICATION forming part of Design No. 26,980, dated April 27, 1897.

Application filed March 11, 1897. Serial No. 627,065. Term of patent 14 years.

To all whom it may concern:

Be it known that I, JAMES S. COPELAND, a citizen of the United States, and a resident of Hartford, in the county of Hartford and State of Connecticut, have invented a new and original Design for a Crank-Shaft Bracket for Bicycles; and I do hereby declare the following, when taken in connection with the accompanying drawings and letters of reference marked thereon, to be a full, clear, and exact description of the same, and said drawings constitute part of this specification.

The drawings represent, in Figure 1, a plan view of the bracket; in Fig. 2, a view in side elevation looking from the right as the device is shown in Fig. 1; in Fig. 3, a view in side elevation looking from the left as shown in Fig. 1, and in Fig. 4 a perspective view of the device.

My invention relates to a design for a bracket or hanger, such as is united to or forms part of the frame of a bicycle or tricycle at a somewhat central and lower part of said frame; and said invention consists in the configuration of the structure, as hereinafter described and as shown in the accompanying drawings.

The bracket has a main body portion *a*, circular in outline when viewed from either end, with a laterally-extending cylindrical part *b*, terminating in a distinct portion *c* of decreasing diameter toward its end. On that end of the body part from which the extension *b* projects a cylindrical enlargement *d* is formed, the rear or inner walls of which unite with and run into the walls of the body portion *a* and of the extensions *b*. The end of the enlarged part *d* presents a substantially flat surface, through which an opening is formed.

The essential feature of my invention is the cylindrical body part, terminating on one end with the enlargement, as shown.

I claim—

The design for a crank-shaft bracket for a bicycle-frame, substantially as shown.

In testimony whereof I have signed this specification in the presence of two subscribing witnesses.

JAMES S. COPELAND.
